DISPLAY HANGER FOR SHOES

Michael Wahl, Searington, N.Y., assignor to Wahl
Associates, Inc., Long Island City, N.Y.

Filed Mar. 28, 1972, Ser. No. 239,001

Term of patent 14 years

Int. Cl. D6—08

U.S. Cl. D6—252

FIG. 1.

FIG. 2.

FIG. 3.

FIG. 5. FIG. 6. FIG. 7.

FIG. 4.

FIG. 1 is a perspective view of a display hanger for shoes showing my new design;

FIG. 2 is a front elevational view thereof;

FIG. 3 is a top plan view thereof;

FIG. 4 is a bottom plan view thereof;

FIG. 5 is a right side view thereof;

FIG. 6 is a rear elevational view thereof; and

FIG. 7 is a left side view thereof.

I claim:

The ornamental design for a display hanger for shoes, substantially as shown.
